(57) **CLAIM**

The ornamental design for an electromagnetic diaphragm pump, as shown in the drawings and described above.

DESCRIPTION

FIG. 1 is a perspective view of an electromagnetic diaphragm pump when seen from the top and left side of the front, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partially cutaway, cross section taken across FIG. 6 along line VIII—VIII.
